Related U.S. Application Data

(57) **CLAIM**

(62) Division of application No. 29/718,569, filed on Dec. 26, 2019.

The ornamental design for a needle holder for endoscopic surgery, as shown and described.

(51) LOC (13) Cl. **24-02**
(52) U.S. Cl.
USPC **D24/143**

DESCRIPTION

(58) **Field of Classification Search**

FIG. 1 is a front perspective view of a needle holder for endoscopic surgery showing our new design in an opened state;

USPC D24/143–148, 133, 127–131, 112–114,
D24/186, 118; 606/181, 185; 604/264,
604/523–528, 272, 187, 158,
604/164.01–164.11, 181, 184, 227

FIG. 2 is a front view of the needle holder for endoscopic surgery of FIG.1, the rear view being a mirror image thereof;

CPC A61B 17/062; A61B 2017/0608; A61B
17/0469; A61B 17/29; A61B 2017/00296

FIG. 3 is a top plan view thereof;

See application file for complete search history.

FIG. 4 is a bottom plan view thereof;

FIG. 5 is a left side view thereof;

FIG. 6 is a right side view thereof; and,

FIG. 7 is a front view of the needle holder for endoscopic surgery of FIG.1 shown in a closed state thereof.

The broken lines show portions of the needle holder for endoscopic surgery that form no part of the claimed design.
